UNITED STATES PATENT OFFICE.

JOHN M. ADAMS, OF CHICAGO, ILLINOIS.

METAL BEDSTEAD.

1,153,590.

Specification of Letters Patent. Patented Sept. 14, 1915.

Application filed April 5, 1911. Serial No. 619,100.

To all whom it may concern:

Be it known that I, JOHN M. ADAMS, a citizen of the United States, and a resident of Chicago, in the county of Cook and State 5 of Illinois, have invented certain new and useful Improvements in Metal Bedsteads, of which the following is a specification.

This invention relates to metal bedsteads.

As is well known, "ornaments", usually 10 made of sheet brass or other thin ductile metal, are very commonly applied to the joints between different members of metal bedsteads for the purpose of imparting a neat and pleasing appearance to the bed- 15 stead.

The object of my present invention is to provide improved and simplified means for securing ornaments for metal bedsteads in position, without the use of screws or the 20 like.

To this end, my invention comprises the various features, combinations of features and details of construction hereinafter described and claimed.

25 In the accompanying drawing, in which my invention is fully illustrated—Figure 1 is a fragmentary side view of two hollow members forming part of the head or foot of a bedstead having an ornament secured 30 thereto in accordance with my invention. Fig. 2 is a vertical sectional view thereof. Fig. 3 is a diagrammatic view substantially similar to Fig. 2, just before the connection is made and illustrating the manner of making 35 the connection; and Fig. 4 is a sectional plan view on the line 4—4 of Fig. 2.

Referring now to the drawings, the reference numerals 1 and 2 designate, respectively, members of a metal bedstead, as for 40 example, a tubular cross member of a head or foot of a bedstead, designated 1, and an upright rod or spindle, designated 2, connected thereto, and 3 is an "ornament" applied to the joint between said members 1 and 2, in accordance with my invention.

The "ornament" 3 forms a sleeve which surrounds the rod or spindle 2 and, in accordance with my invention, is secured in position in the following manner:—Formed 50 in the side of the hollow member 1 is a hole 4, which is adapted to receive the end of the rod or spindle 2. Said hole or opening is made larger than the end of the rod or spindle 2, which engages the same, the difference in size being substantially equal to

twice the thickness of the metal from which the "ornament" 3 is formed. Formed around the open end of the "ornament" 3 adjacent to the transverse member 1, is a flange 5, which is adapted to enter the hole 60 or opening 4 and, after being inserted therethrough, is interlocked with the inner edges of said hole or opening by expanding the end of said "ornament" on which said flange 5 is formed. 65

In practice, the expansion of said "ornament" to effect interlocking of the flange 5 thereon with the inner surface of the transverse member 2 around the hole or opening 4 therein, may be conveniently effected by 70 the process of inserting the end of the rod or spindle 2 through the opening 4 in the member 1, in the following manner:—The opening in the end of the "ornament" 3 on which the flange 5 is formed, is made smaller 75 than the corresponding end of the rod or spindle 2, this difference in size corresponding to the desired expansion of said sleeve. The sleeve is then placed over the end of the rod or spindle 2 with the end of said rod 80 or spindle bearing against the inner side of said "ornament" around the flanged end thereof. The flanged end of the "ornament" 3 is then inserted through the hole or opening 4 in the member 1, the relative positions of the parts at this stage of the operation being shown in Fig. 3. Pressure is now exerted endwise on the rod or spindle 2 to force it through the flanged end of the "ornament" 3, which, owing to the ductility 85 of said "ornament", will operate in an obvious manner to expand the flanged end of said "ornament" and cause the flange 5 thereon to expand into interlocked engagement with the inner surface of the member 1 around the hole 4 in the manner desired. 90

Not only will the rod or spindle 2 operate to secure the flange 5 in engagement with the hollow member 1, but said "ornament" will have strong frictional engagement with said rod or spindle 2, which will, in turn, operate to hold said rod or spindle in position. Both said "ornament" and said rod or spindle will thus be secured in position without the use of screws or bolts, in the 100 manner desired. 105

I claim:—

1. A hollow member of a bedstead or the like, provided with an opening in the side thereof, a hollow "ornament" and means for 110

- securing said "ornament" into the opening in the side of said hollow member, said means comprising an out-turned flange on said "ornament" adapted to enter the opening in said hollow member and to be interlocked with said hollow member within the same by expansion of the portion of said "ornament" on which said flange is formed, substantially as described.
10. 2. A hollow member of a bedstead or the like, provided with an opening in the side thereof, a hollow "ornament" and means for securing said "ornament" into the opening in the side of said hollow member, said means comprising an out-turned flange on said "ornament" and a second bedstead member inserted through said "ornament" into said hollow bedstead member, the flange on said "ornament" being initially smaller than the hole in said hollow member and the hole through the portion of said "ornament" on which said flange is formed being initially smaller than said second bedstead member, the relation being such that inserting said second bedstead member through said "ornament" will expand the portion of said "ornament" on which said flange is formed and will interlock said flange with said hollow member within the hole or open-

ing therein in which said "ornament" is secured, substantially as described.

3. A bedstead, comprising a hollow first member, a second member and a hollow "ornament," said hollow first member being provided with a hole in the side thereof and said "ornament" being expansible and having a flange formed thereon initially smaller than the hole in said hollow first member, and said second member inserted through said "ornament" into said hollow first member, the opening through said "ornament" being initially smaller than the end of the second member, the relation being such that inserting said second member through said "ornament" will expand said "ornament" and interlock the flange thereon with the hollow first member around the hole therein within said hollow first member, substantially as described.

In testimony, that I claim the foregoing as my invention, I affix my signature in presence of two subscribing witnesses, this 28th day of March, A. D. 1911.

JOHN M. ADAMS.
